C. GASCARD

MINE PROP

Filed Oct. 13, 1926

Inventor:

Charles Gascard

UNITED STATES PATENT OFFICE.

CHARLES GASCARD, OF WIESBADEN, GERMANY.

MINE PROP.

Application filed October 18, 1926, Serial No. 141,402, and in Germany June 8, 1926.

My invention relates to a yielding mine prop composed of two profile irons the faces of which can be made to slide upon each other, and are held in frictional contact with each other by means of a double-armed clamp oscillative upon one prop member. This clamp is adapted to slide upon its pivot and thereby vary the respective lengths of its two lever arms. My invention resides in the feature that one end of the oscillatory clamp affects, by means of an eccentric, the movable prop member in such a manner that when the load on the prop exceeds the pressure limit to which the prop has been initially adjusted, the eccentric, in consequence of the cooperation of the movable member, is revolved by the latter and presses it with increased force against the stationary prop member, the pressure on which is consequently transmitted over a frictional surface which increases in proportion to the yielding effect. In a further form of application of my invention the eccentric is provided with a wedge-shaped stop tangential to the point of maximum eccentricity, which as the pressure increases eventually presses with its one wedge-face flat against the movable prop member, and the opposite wedge-face of which serves as point of application for a hammer when the prop is being set into its initial operative position. Within this tangential stop and on the face of it which is turned away from the prop there is further provided an orifice for the introduction of a lever serving to turn back and thereby to release the eccentric.

The yielding mine prop as constructed according to my invention has the advantage of consisting entirely of metal, and thus has no wooden parts susceptible to the effects of dampness and the weather, and is not dependent for its adjustment upon screws or such like separate parts. Owing to the pivoting point of the double-armed lever being made free to slide in the manner described, it is possible for the mine prop as herein described by altering the length of the lever-arm and by varying the initial setting of the eccentric, to be adjusted for different yield limits and also for varying maximum loads and varying yield extents. The eccentric being mounted on an oscillatory lever, the initial pressure exercised when the eccentric is moved lies rather high, and since the eccentric as the yield increases affects an increasing frictional surface be-

tween both prop members, a slight turning movement produced by the cooperation of the movable prop member is always sufficient to set the prop anew for increasing pressures, and this in such a manner that the prop is not deprived of its property of being a yielding mine prop.

I will now describe my invention with reference to the drawing forming a part of this application, and in which

Fig. 1 is an elevation of a complete prop.

Fig. 2 is a similar partial view on an enlarged scale, and

Fig. 3 is a section along the line 3—3 of Fig. 2.

The mine prop consists of two parts 1 and 2, preferably of equal length and made from iron I-beams. The stationary prop member 2 is provided with a pair of base-brackets 2^a, and the movable prop member 1 with a pair of brackets 1^a for the wooden cross pieces of the match-boarding of the mine roof. The guide straps 3, 3 serve to maintain in connection and in mutual position the two opposed flanges of both profile irons 1 and 2. Through the upper part of the stationary prop member 2 which is strengthened by disks 4^a there passes a pivot bolt 4, on which is mounted oscillatively by means of a slot 5, a double-armed clamp 6. This clamp 6 embraces both prop members 1 and 2, extending with its two ends beyond either. On the one end of the oscillating clamp 6 is loosely mounted on a bolt 7 an abutment member 8 lying with its right-angled abutment surface against the outer flange of the stationary prop member 2. On the opposite end of clamp 6 is oscillatively mounted on a bolt 9 an eccentric 10, which is provided, tangentially at the point of its maximum eccentricity, with a wedge-shaped enlargement 10^a adapted to act as a stop. When the prop is erected and set as shown in Fig. 1, the wedge-shaped stop is out of contact with the movable prop member 1. When the prop is subjected to the maximum pressure or load, the pressure transmitting eccentric 10 is turned to the point of its maximum eccentric throw, and the rear face of its stop 10^a is in frictional contact with the movable prop member 1. The friction between this rear surface of the stop 10^a and the movable prop member 1 is, owing to the acute-angled position of the stop 10^a so great, that every increase in the load tends to effect an oscillation of the double-armed clamp 6, by

which the friction between the two prop members 1 and 2 is still further increased.

The setting of the prop at the time of erection is effected by strokes of a hammer 5 on the front surface of stop 10^a, i. e. the surface turned away from prop member 1. To enable the operator to readily release the eccentric 10, there is provided in that thickened part of it which forms the wedge-shaped stop 10^a, an orifice 11 for the introduction of a lever of any required length.

The lower yielding limit depends upon the initial operative setting of the prop, i. e. on the degree to which eccentric 10 is being 15 driven in, and the extent of the yield on the length of the eccentric operative surface of the eccentric 10. By varying the respective length of the lever-arms of the double-armed clamp 6 it is possible to set the initial operative point of the eccentric 10 either nearer 20 to or remoter from the point of maximum eccentric throw, for example, by interchanging the abutment member 8 for a thicker one, or by setting it back from the flange of prop 25 member 2 by interposed plates. As with every oscillatory movement of the double-armed clamp 6 the friction between abutment 8 and prop member 2 has to be overcome, the adjustment of the prop may be 30 altered by increasing or decreasing size of the frictional surface, i. e. by making abutment 8 longer or shorter, respectively.

What I claim as my invention and desire to secure by Letters Patent of the United 35 States is:—

1. A mine prop, comprising, in combination, a stationary and a movable prop member, the latter being adapted to yield longitudinally with respect to the stationary member under load, an oscillatory clamp member 40 having a pivotal connection with the stationary member and adapted to maintain said prop members in mutual frictional contact with each other, an eccentric in cooperative contact with said movable prop member and revolvably mounted at one end of said clamp member to exert an increasing pressure against said prop member upon movement thereof under its load causing said 45 eccentric to revolve, and an abutment member mounted at the other end of said clamp member and between said other end and said stationary member, thereby to maintain said other end in operative relation with respect 50 to the prop members.

2. A mine prop, comprising, in combination, a stationary and a movable prop member, the latter being adapted to yield longitudinally with respect to the stationary member under load, an oscillatory clamp member 60 having a pivotal connection with said stationary prop member and adapted to maintain said prop members in mutual frictional contact with each other, means to vary the 65 operative length of the clamp member, an

eccentric in cooperative contact with said movable prop member and revolvably mounted at one end of said clamp to exert an increasing pressure against said prop member upon movement of the said prop member under its load causing said eccentric to revolve, and an abutment member mounted between the other end of said clamp member and said stationary member and contacting against the stationary prop member. 75

3. A mine prop, comprising, in combination, a stationary and a movable prop member, the latter being adapted to yield longitudinally with respect to the stationary member under load, an oscillatory clamp member 80 having a pivotal mounting on said stationary prop member and adapted to maintain said prop members in mutual frictional contact with each other, an eccentric in cooperative contact with said movable prop member and revolvably mounted at one end of said clamp member to exert an increasing pressure against the movable prop member upon movement of said prop member under its load causing said eccentric to revolve, an 85 abutment member loosely mounted at the other end of said clamp member to maintain itself against the stationary prop member during movement of said movable prop member, said eccentric having a projecting portion provided with a flat surface disposed tangentially to the point of maximum eccentricity of the eccentric, said tangential surface flatly engaging said movable prop member when the latter is subjected to maximum load. 90

4. A mine prop, comprising, in combination, a stationary and a movable prop member, the latter being adapted to yield longitudinally with respect to the stationary member under load, an oscillatory clamp member having a pivotal mounting on said stationary prop member and adapted to maintain said prop members in mutual frictional contact with each other, an eccentric in cooperative contact with said movable prop member and revolvably mounted at one end of said clamp member to exert an increasing pressure against the movable prop member upon movement of said prop member under its load causing said eccentric to revolve, an abutment member disposed at the other end of said clamp member normally to maintain said other end of the clamp in operative relation with respect to the stationary prop member, said eccentric having a projecting portion provided with a flat surface disposed tangentially to the point of maximum eccentricity of said eccentric, said surface flatly engaging against the movable prop member when the latter is subjected to maximum load, and another surface on said projection providing a point of application for a hammer in initially setting the prop in operative position. 100 105 110 115 120 125 130

5. A mine prop, comprising, in combination, a stationary and a movable prop member, the latter being adapted to yield longitudinally with respect to the stationary member under load, an oscillatory clamp member having a pivotal mounting on said stationary prop member and adapted to maintain said prop members in mutual frictional contact with each other, an eccentric 10 in cooperative contact with said movable prop member and revolvably mounted at one end of said clamp member to exert an increasing pressure against the movable prop member upon movement of said prop member under its load causing said eccentric to revolve, an abutment member disposed at the other end of said clamp, to maintain said clamp operatively related to the stationary prop member, a projecting portion 15 formed on said eccentric and having a flat surface disposed tangentially to the point of maximum eccentricity of said eccentric, said surface flatly contacting against said movable prop member when the latter is subjected to maximum load, said projecting portion being provided with means adapted 20 to receive an eccentric release lever.

6. A mine prop, comprising, in combina-

tion, a stationary and a movable prop member, the latter being adapted to yield longitudinally with respect to the stationary member under load, an oscillatory clamp member having a pivotal mounting on said stationary prop member and adapted to maintain said prop members in mutual frictional contact with each other, an eccentric 30 in cooperative contact with said movable prop member and revolvably mounted at one end of said clamp member to exert an increasing pressure against the movable prop member upon movement of said prop member under its load causing said eccentric to revolve, an abutment member mounted between the other end of said clamp member and stationary prop member, thereby to maintain said clamp in operative relation with respect to the stationary prop member, a projecting portion on said eccentric having a flat surface disposed tangentially to the point of maximum eccentricity of the eccentric, said projection being provided with a surface serving as a point of application for a hammer to be used in setting the prop in its initial operative position, and having therein an orifice for the insertion of an eccentric release lever.

CHARLES GASCARD.
